CONNECTOR CLIP

William T. Koehlinger, Kalamazoo, Mich., assignor to Borg-Warner Corporation, Chicago, Ill., a corporation of Illinois

Application February 28, 1948, Serial No. 12,012

1 Claim. (Cl. 151—41.75)

1

This invention relates generally to window sash assemblies and more particularly to metal sash or frames embodying improved principles of design and construction.

An important object of the invention is to provide a sash of which the stiles and rails thereof are each comprised of a base member and a cover member, the members being designed and constructed to support and clamp either a glass, screen, or other desirable sheet material therebetween.

A particular object of the invention is to provide each of the base members with walls to form a longitudinal guideway which slidably supports connectors of a character to receive screws extending through holes provided therefor in the cover member whereby to detachably secure the members together, said connectors also providing means whereby a handle or some other device may be attached to the sash.

Another important object of the invention is to design and construct a novel resilient connector which is readily attachable to the base member by inserting either extremity of the connector into either end of the longitudinal guideway or by pressing the same broadside into the guideway to a snap locking position, after which the connector may be manually moved and frictionally held at any location desired to receive a screw extending through the cover member.

An additional object of the invention is to provide a connector of such a character that at least a portion thereof will be placed under tension when the cover member is anchored down against the base member by the screws, the purpose of which is to prevent accidental loosening of the screws as well as vibration between such members.

Another object of the invention is to provide the base member with inner and outer formations which serve as reinforcements to impart rigidity to such member, the inner formation being fashioned to provide a groove or grooves for the reception of means for attaching a screen to the sash or a gasket for glass or other material.

A further object of the invention is to provide a novel fastener which acts in the dual capacity of either pressing one of the sashes in its normal position against an abutment of a supporting frame to lock the sash in the frame or as a safety

2

catch or arrestor to hold the sash in its ventilating position and prevent the sash from inadvertently falling out of a supporting frame therefor.

Another object of the invention is to provide an improved sash supporting frame and unique means for mounting the frame in a window structure.

A further object of the invention is to provide a novel sash assembly comprised of parts which can be economically manufactured and assembled together on a production basis.

Many other objects and advantages of the invention will become apparent after the description hereinafter set forth is considered in conjunction with the drawing annexed hereto.

In the drawings:

Figure 1 is a front elevational view of the assembly embodying the invention;

Figure 2 is a transverse enlarged partial sectional view taken substantially on the line 2—2 of Figure 1, illustrating a portion of a window sash and the way it is mounted with respect to a window structure;

Figure 3 is a transverse enlarged partial sectional view taken substantially on the line 3—3 of Figure 1, depicting constructional details of a screen sash and its relation to the window sash;

Figure 4 is a transverse enlarged section taken substantially on the line 4—4 of Figure 1, showing the screen sash and the way it is mounted with respect to the window structure;

Figure 5 is a sectional enlarged view taken substantially on the line 5—5 of Figure 1, illustrating a safety catch embodying improved principles of design and construction;

Figure 6 is a perspective view, on an enlarged scale, of one of the connectors employed to attach members of the sashes together; and

Figure 7 is an enlarged perspective view illustrating a portion of one of the base members forming a component part of a sash.

As exemplified particularly in Figures 1, 2 and 4 of the drawing, the assembly embodying the invention includes a window sash 1 and a screen sash 2 supported in a rectangular frame 3. The assembly is preferably constructed of die cast aluminum or other material suitable for the purpose. It is substantially of uniform thickness, and adapted to be secured in a vertical position in

an opening 4 relative to a stop 5 provided on a window structure 6.

The horizontal top and bottom members 7 and 8, and vertical side members 9 of the sash supporting frame are preferably of channel shape. The top member 7 is provided with an integral inner depending flange 10 and the bottom member 8 with an inner upturned flange 11. These flanges provide abutments for the sashes. The depending flange 10 also serves to prevent the entry of rain, snow, and other foreign matter in between the upper window sash and the frame.

A plurality of holding means are carried by the supporting frame for pressing and detachably holding the sashes and frame assembled. Such means preferably include a pair of fasteners 12 secured adjacent the upper corners of the frame. Each fastener includes tab portions 13 through which screws of rivets 14 pass into the frame, and an intermediate offset portion 15 provided with an integral finger 16 depending in spaced relation to the upper window sash. The free extremity of each finger is formed with a curved or bowed portion 17, which engages the window sash and when it is being raised in the supporting frame more or less pilots the sash into place.

A second pair of fasteners 18 are secured to the side members 9 of the frame adjacent to the parting line between the sashes, and each includes a tab portion 19 for attaching the fastener to the frame and an offset portion 20 formed with a pair of aligned upright and depending yieldable leg portions 21 and 22. The free ends of the leg portions are formed with curved or bowed portions 23, which respectively bear against the window and screen sashes. These fasteners are so located that the lower screen sash may be swung inwardly as illustrated in Figure 5, without damaging the depending leg portions 22 of the fasteners. It will be noted that with this arrangement the window sash may be readily removed from the frame when lowered to the position formerly occupied by the screen sash.

A third pair of adjustable fasteners or catches are secured adjacent to the lower corners of the sash frame, and these are operable to one position to lock the sashes in the frame and to another position to permit the removal of the sashes or to hold the lower sash 2 in ventilating position. Each of these fasteners or catches includes a plate 24 secured to the frame by rivets or screws 25 and by a pair of headed pins 26 disposed in slots 27 formed in the upper marginal edge of plate 24 so that the heads overlie the plate. Each plate is provided with an integral upwardly extending spring tongue 28 which projects through a rectangular opening 29 provided therefor in a catch lever 30. The free end of the spring tongue is provided with an inturned portion 31 to hold the lever associated with the plate 24. It will be noted that the inner end of each lever and a marginal edge of the opening therein are respectively bevelled as indicated at 32 and 33, and that its outer extremity is provided with a pair of curved portions 34 and 35 and a flat rest portion 36 therebetween. The arrangement is such that the screen sash may be pulled inwardly by a handle 37 to the full line ventilating position illustrated in Figure 5 so that the sash is seated on the rest portion 36 and held in place by the curved portions 34 and 35. The spring tongue is so designed and constructed that it bears against the bevelled edge 33 of the opening to force the bevelled end 32 of the lever against the plate 24 to maintain the lever in such full line

position. The levers may be swung upwardly by grasping the curved portions 35, which serve as handles, to lift the sash into the frame so that the tongues will act to press the curved portions 34 of the levers against the sash as illustrated by the dotted line position in Figure 5. These fasteners or catches also serve to catch or arrest the falling out of the lower sash in the event it is inadvertently bumped inwardly.

10 Various means may be employed to mount the sash supporting frame 3 in the window structure opening 4, but as herein illustrated such means preferably includes, among other things, a channel fitting 38 adjustable in the top channel member 7 of the frame. This fitting is attached to the header portion of the window structure by screws 39 and also by a strip 40, the latter also being secured to the header by screws 41. Another channel fitting 43, adjustable in the bottom member 8 of the frame, rests on the inclined sill portion 42 of the window structure. This arrangement has proven desirable in practice because the complete assembly comprising the sashes and frame may be easily and quickly installed and adjusted in the window structure to the position desired, even though the height of the opening in such structure may be somewhat in excess of the overall length of the frame. In other words, the mounting means is of such a character that the sash supporting frame may be fitted into window structures in which the height of the openings therein may vary. With this arrangement, the general appearance of the complete set-up is enhanced.

35 The window and screen sashes, except for a few minor structural differences are identical. The window sash includes upper and lower rails or members 44 and 45 and stiles or members 46, and the screen sash similarly includes upper and lower rails 47 and 48 and stiles 49. The lower rail 45 of the window sash is preferably provided with an integral depending lip portion 50 which overlies the outer surface of the upper rail 47 of the screen sash to exclude rain, snow and any foreign matter from entering between such rails. 40 The lower rail 48 of the screen sash may be provided with an integral inclined portion 51, which overhangs the upturned flange 11 on the bottom member 8 of the sash supporting frame 3 to deflect and exclude any of the elements above referred to from entering between such lower rail and such bottom member.

45 The rails and stiles of the sashes are each comprised of a base member and a cover member. Figure 7 illustrates one of the stiles, and it will be apparent that, except for the lip and inclined portions 50 and 51 on the lower rails of the window and screen sashes, respectively, the base members 52 are all identical and, therefore, a description of one will be sufficient. The cover members 53 associated with the base members of the window sash are slightly different from the cover members 54 associated with the base members of the screen sash.

50 Each of the base members 52 preferably includes a base portion 55, an outer wall 56, an inner wall 57 defining the inner longitudinal marginal edge of the base portion, a wall 58 spaced inwardly from the inner wall 57, and a pair of corresponding guide walls 59 and 60 which provides a longitudinal guideway 61 for one or more connectors 62 as exemplified in Figure 6. All of the walls are more or less of the same thickness and arranged in spaced apart 55 parallel relationship at right angles to the base

portion. The outer longitudinal extremities of the guide walls 59 and 60 are preferably formed with oppositely disposed inturned portions 63, parallel to the base portion, and spaced apart to provide an entranceway 64 through which the connectors 62 may be projected and the screws inserted into the connectors. These inturned portions assist in holding the connectors in the guideway and also serve as lands for the cover. The outer wall 56 is preferably provided with an inset portion 65, parallel to the base, to form an additional land for the cover. More specifically in this respect, the outer surfaces of the lands are arranged in the same plane to provide substantial support for the cover, and so that its outer planar face is flush with the outer edge surface 66 of the outer wall. The outer wall 56 and adjacent guide wall 60 are constructed to provide a channel formation 67. The inner wall 57 and wall 58 are substantially identical and of a height somewhat less than that of the other walls. The walls 57 and 58 are designed and constructed to provide a slot 68 and the guide wall 59 and wall 58 a groove 69 adjacent to slot 68.

This arrangement imparts stability to the base member, particularly adjacent its inner longitudinal extremity which provides a support for the glass, screen or other material which will now be described. As exemplified in Figure 2, the edge of the glass 70 is provided with a gasket 71 of rubber or other yieldable material, and when the cover 53 is tightly secured in place portions of the gasket will be forced against the walls 57 and 58 which form lands and also into the slot 68 and groove 69 and against the guide wall 59 to provide a firm yet yieldable seal and mounting for the glass. It will be noted that a portion of the gasket is interposed between the glass and the cover 53, and that the size of the rabbet formed by the guide wall 59 and walls 57 and 58, and the thickness of the glass and gasket are so proportioned that the gasket will be properly distorted or compressed when the cover is forced against the lands above referred to so as to provide not only a good clamping action but present a trim appearance to the sash generally.

Attention is directed to the fact that the cover 53 is preferably provided with an integral rib portion 72 which projects into the channel formation 67 to strengthen the structure.

The connectors 62 employed to assist in securing the cover member to the base member are of a novel character, and as clearly illustrated in Figure 6, each is preferably of spring steel and of channel construction having a bottom wall 73 and side walls 74. The central portion of the bottom wall is provided with inturned yieldable portions 75, the free ends of which are formed with semi-circular notches 76 to provide an opening for the threaded end of a screw 77. The outer ends of the bottom wall are provided with inclined tongue portions 78.

The side walls of the connector are preferably arranged in a converging relationship and the free longitudinal edge portions may be slightly inturned as at 79. The opposite ends of the side walls are provided with yieldable locking fingers 80 formed by the interruptions or notches 81.

Each connector is preferably designed and constructed for broadside entry into the guideway 61. To insert the connector into such guideway it is directed to a position in which the inturned portions 79 on the side walls 74

of the connector engage the inturned portions 63 on the guide walls 59 and 60, whereupon the connector is pressed downwardly into the guideway causing the locking fingers to yield and when the ends of the fingers pass beyond the inturned portions 63, such fingers will automatically snap or flex outwardly, and catch behind portions 63 to lock the connector in the guideway. It may then be moved to any longitudinal position desired so that the opening defined by the semi-circular notches will receive the threaded end of the screw 77. With this set-up the screw when tightened will cause the inturned portions 75 on the bottom wall to react and serve to resist the screw from loosening. Also assisting in this respect, are the tongue portions 78 which are depressed when the cover is secured in place.

Attention is directed to the fact that the various parts are so constructed and arranged that either end of the connector may be inserted into either end of the guideway 61 by merely contracting the locking fingers. It is to be understood, of course, that such end insertion would be completed before the stiles and rails or members of the sashes are connected together.

Attention is also directed to the fact that the handle 37, above referred to, is attached to the lower rail of the screen sash by screws passing through the ends of the handle and through the cover 54 into the connectors.

The covers 54 associated with the base members 52 of the screen sash, as alluded to above, are slightly different from the covers 53 forming component parts of the window sash. Each of the covers 54 is substantially planar in character and provided with a right angled wall portion 82 adjacent its inner longitudinal edge which is adapted to lie in the same plane as the wall portion 57 on the base member when the cover is secured in place. The screen is adapted to be anchored adjacent its marginal edges, to the sash by attaching means preferably in the form of a single wire 83 provided with corresponding undulations disposed in the interstices of the screen. Certain of the undulations are seated in the slot 68 of the base member, while other undulations are arranged in back of the wall 82 on the cover. With this arrangement, the screen is securely detachably locked in place. It will also be evident that the slot 68 serves to retain the attaching means in place in one instance and at least receive a portion of the gasket 71 in another instance.

It may be noted that the glass pane or screen may be readily replaced in the event the glass becomes broken or the screen is torn, as it is only necessary to detach the screws and the cover members 53 or 54 of the metal frame to remove the broken glass pane or torn screen and thereafter, upon the ready insertion of a new pane or screen within the frame, to attach the screws and cover members to the frame.

In view of the foregoing description, it will be apparent that improved principles of design and construction have been embodied in sash construction with means for mounting the same, and although the preferred form of the invention is exemplified, it is, of course, obvious that the structure may be varied or modified in different respects without departing from the true spirit of the invention, as defined in the claim.

I claim:

A connector clip for a window type frame comprising a channel-shaped structure having a bot-

torn wall and spaced, generally convergent side walls; a pair of inturned, opposed, yieldable, thread-engaging fingers in said bottom wall; oppositely directed, resilient tongue portions formed at each end of the bottom wall; and yieldable locking tabs formed from the side walls at the terminal and base ends of said side walls.

WILLIAM T. KOEHLINGER.
